COASTER CHEST

Jeffrey Snyder, 5225 Collins Ave.,
Miami Beach, Fla. 32935

Filed Nov. 15, 1973, Ser. No. 416,270

Term of patent 14 years

Int. Cl. D7—99

U.S. Cl. D7—45

FIG. 1.

FIG. 2.

FIG. 3.

FIG. 4.FIG. 1 is a three-quarter, front perspective view of a coaster chest showing my new design;

FIG. 2 is a three-quarter rear perspective view thereof;

FIG. 3 is a three-quarter front perspective view thereof in an open condition; and

FIG. 4 is a top plan view of FIG. 3 on an enlarged scale.

The bottom or base of the coaster chest is substantially flat and unornamented.

I claim:

The ornamental design for a coaster chest, as shown and described.
